[57] CLAIM

The ornamental design for a sling chair, as shown and described.

DESCRIPTION

FIG. 1 is a perspective view of a sling chair showing our new design;

FIG. 2 is a front elevational view thereof;

FIG. 3 is a left side elevational view thereof, the right side view being a mirror image of that shown;

FIG. 4 is a top plan view thereof;

FIG. 5 is a rear elevational view thereof;

FIG. 6 is a bottom plan view thereof; and,

FIG. 7 is a perspective view of an alternative embodiment of the design in which the frame is visible through the fabric. The seat and backrest of the sling chair each include fabric stretched across a frame.

The other views of this embodiment correspond to FIGS. 1 through 6, the sole difference being that the frame is visible through the fabric.
